UNITED STATES PATENT OFFICE.

MARTIN ELMÉR, OF HASTINGS, MICHIGAN.

COIN-HOLDER.

1,198,204.

Specification of Letters Patent. Patented Sept. 12, 1916.

Application filed March 4, 1916. Serial No. 82,096.

To all whom it may concern:

Be it known that I, MARTIN ELMÉR, a citizen of the United States, and a resident of Hastings, in the county of Barry and State of Michigan, have invented a new and Improved Coin-Holder, of which the following is a full, clear, and exact description.

My invention relates to coin holders of the type in which a box or casing receives the coins, and is provided with a spring to press the coins forwardly, means being provided for removal of the coins in succession.

More particularly the invention relates to a coin holder of the class referred to, in which a cover is pivotally mounted to swing in its own plane, whereby to displace the front coin and bring the same to a position to be grasped for the complete withdrawal of the coin.

20 The invention is characterized also, by a registering mechanism associated with the swinging cover so that the swinging of the cover operates the registering wheels.

The invention will be particularly described in the specific description following.

Reference is to be had to the accompanying drawings forming part of this specification in which similar reference characters indicate corresponding parts in all the views.

Figure 1 is a longitudinal vertical section of a coin holder embodying my invention in a form to separately accommodate coins of different denominations; Fig. 2 is an end view thereof, one of the covers being shown closed and the other partly open; Fig. 3 is a cross section on the line 3-3, Fig. 1; Fig. 4 is a cross section on the line 4-4, Fig. 1.

In the illustrated example, I have shown 40 two containers, 10, 10^a, which are alike except as to their diameter, the one being adapted to receive smaller coins than the other. The containers, 10, 10^a, are preferably cylindrical and two of these, as in 45 the example shown, may be held within a casing 11 stamped from sheet metal in two parts, each having a flat central portion and semi-cylindrical ends, the flat central portions when the two casing members are 50 placed in position, being united by rivets 12 or other suitable means and constituting a web 11^a between the two containers.

As the containers are alike, except as to 55 diameter, it will suffice to describe in detail but one container. The preferably cylindrical body of the container is closed at one

end by a cap 13 having a handle 14 and an inwardly extending flange 15 snugly fitting the interior of the container. Any suitable means may be provided to hold the cap in place, there being shown for the purpose, beads 16 struck up from the flange 15 and adapted to be sprung into slots or depressions 17 in the body of the container.

A compression spring 18 in the container 65 abuts at one end against the cap 13 and is adapted to receive the coins A at its opposite end, whereby to press the coins toward the cover 19.

Each cover 19 is mounted on a pivot 20, 70 here shown as a pin extending through a lug 21 on the cover, and into sockets 22, formed by the web 11^a.

On the inner side of the cover is a depending lug 23 adapted to engage the edge 75 of the foremost coin A when the cover 19 is swung on its pivot 20, whereby to displace said coin laterally through registering slots, 24, 25, in the container 10 or 10^a, and casing 11. In the closed position of the cover, the 80 lug 23 is received in a recess 26 in the container.

I provide a spring 27, here shown as a plate spring, to bear against the cover 19, the spring tending normally to hold the 85 cover in the closed position and acting to return the cover to the closed position after an opening movement of the cover to displace a coin. Said spring 27 is secured at one end to a pin 28 fastened to the web 11^a or other fixed part of the structure, and it acts as a pawl to actuate a register.

The register includes a suitable casing 29 on the cover 19 and any suitable number of registering wheels, indicated at 30. On 95 the spindle or arbor 31 of the initial registering wheel, a ratchet wheel 32 is secured with which the spring 27 engages as a pawl. Thus, when the cover is swung to the open position as shown at the left of Fig. 2, the 100 spring 27 will turn the ratchet 32 to the extent of one tooth; the reaction of the spring will close the cover 19, the end of the spring slipping over the ratchet.

Having thus described my invention I 105 claim as new and desire to secure by Letters Patent:

1. A coin holder including a container having a lateral coin outlet at one end, a laterally swinging member adapted to engage and displace a coin, a register carried by said member, said register including a 110

ratchet wheel to actuate the register and a spring engaging the said ratchet and acting to turn the same by a coin displacing movement of the said swinging member, said 5 spring exerting pressure on the said swinging member and acting to return the same after a coin-displacing movement.

32. A coin holder having a cover at one end and pivoted to swing laterally, means 10 on the cover to engage and displace a coin laterally, a register mounted on and movable with the cover, a ratchet in fixed rela-

tion to a rotary element of the register, and a spring engaging said ratchet to turn the same by the movement of the cover, said 15 spring acting to return the cover to its closed position.

In testimony whereof I have signed my name to this specification in the presence of two subscribing witnesses.

MARTIN ELMÉR.
